(57) **CLAIM**

The ornamental design for a rearview camera for automobile as shown and described.

DESCRIPTION

FIG. 1 is a top, front and right side perspective view of a rearview camera for automobile showing my new design; FIG. 2 is a top, rear and left side perspective view thereof; FIG. 3 is a front elevational view thereof; FIG. 4 is a rear elevational view thereof; FIG. 5 is a left side view thereof; FIG. 6 is a right side view thereof; FIG. 7 is a top plan view thereof; and, FIG. 8 is a bottom plan view thereof.
The broken lines in the drawings illustrate portions of the rear view camera for automobile which form no part of the claimed design.
